UNITED STATES PATENT OFFICE.

HENRY H. HOLTKAMP, OF LAKewood, OHIO.

PNEUMATIC ACTION.

1,100,568.

Specification of Letters Patent. Patented June 16, 1914.

Application filed December 3, 1909. Serial No. 531,282.

To all whom it may concern:

Be it known that I, HENRY H. HOLTKAMP, a citizen of the United States, and a resident of Lakewood, in the county of Cuyahoga and State of Ohio, have invented a new and Improved Pneumatic Action, of which the following is a full, clear, and exact description.

- The invention relates to musical instruments, such as pipe organs, and the like, and its object is to provide a new and improved pneumatic action, arranged as a conflating device for the union, coupling, confluence or conjunction of a plurality of ducts controlling the speaking apparatus of sounding or mechanical devices, or of independent ducts or other means directly or indirectly for the various functions found in a pneumatic action.
- For the purpose mentioned, use is made of a selecting device which I prefer to call a conflator, having a suspended double acting valve mechanism for vertical ports manipulating two sources of exhaust, either directly from a manual key, pallet or a valve, or from a pneumatic, electro pneumatic or an auto-playing device, and exhausting independently the operating duct for either a primary or power pneumatic or other device, without one source of exhaust interfering with the other, and whether either source singly or both sources are operated simultaneously.

A practical embodiment of the invention is represented in the accompanying drawings forming a part of this specification, in which similar characters of reference indicate corresponding parts in all the views.

Figure 1 is a transverse section of the pneumatic action; Fig. 2 is a sectional side elevation of the same on the line 2—2 of Fig. 1; Fig. 3 is an elevation of the pneumatic action as applied to a pipe organ; Fig. 4 is a sectional side elevation through the wind chest and pipe. Fig. 5 is a similar view through the valve box. Fig. 6 is a sectional side elevation of the "On" and "Off" device which is controlled by a stop pallet.

The main or operating duct A, for power pneumatic T or other device, leads to oppositely-arranged ports B, B', controlled by a double-acting valve C, C', and connected with branch ducts D, D', of which the branch duct D leads to an "On" and "Off" device Y, such, for instance, as shown in Fig. 3 and controlled by a key pallet R',

while the other branch duct D' leads to a duct A' of a preceding conflator, that is, the duct A' leads to ports B², B³, controlled by a double-acting valve E, E', and the said ports B², B³, connect with branch ducts D², D³, of which the branch duct D² leads to an "On" and "Off" device Y or other source of exhaust, while the branch duct D³ leads to a duct A² forming part of another preceding conflator, having ports B⁴, B⁵ controlled by a double-acting valve F, F', and connected with branch ducts D⁴, D⁵, of which the duct D⁴ leads to an "On" and "Off" device Y or other source of exhaust, while the duct, D⁵ leads to another source of exhaust. The double-acting valves C, C', E, E' and F, F' are alike in construction, each being mounted to swing from the upper end of its stem as a fulcrum, the stem of each valve, as shown, being flexible and fastened at its upper end by a block G and a screw H to the wall of the corresponding duct D, D', D², D³ or D⁴, D⁵, so that the double valve is suspended. The block G is preferably slotted, as indicated in Fig. 2, to permit convenient adjustment of the block to suit circumstances. The bodies of each double-acting valve are connected with each other by a spanner stem I, to hold the valves spaced apart, so that when one valve is closed the other is opened and vice versa, as will be readily understood by reference to Fig. 1. The nuts I' on the spanner stems I are preferably made of leather or other cushioning material, to form a flexible bearing for the valves when the latter are seated. Adjacent the ducts D, D² and D⁴ are arranged diaphragm chambers J, J', J², containing diaphragms K, K', K² connected by stems L, L' and L² with the free ends of the valves C, E and F of the double-acting valves previously mentioned, the said diaphragm chambers and their diaphragms and stems forming parts of and being connected by connections O, O' O² with "On" and "Off" devices Y', which are controlled by stop pallets R², as shown in Fig. 6, for actuating the double valves correspondingly. Each of the stems L, L', L² is provided with a cushion M adapted to be seated against the outer wall of the diaphragm chamber, thus insuring a silent operation when striking the wall of the chamber at the time pressure is exerted in the diaphragm chamber.

The casing N of the action is made in vertical sections, fastened together and ar-

ranged as shown in Fig. 1, to permit convenient access to the parts.

It is understood that the spanner stem I permits a simultaneous closing or opening 5 of the double-acting valve C, C', on the ports B, B', that is, at least one port leading to the duct A is open, thereby allowing an unimpeded connection and inflation of the pneumatic whenever both keys or other 10 devices are released. It will also be noticed that by the arrangement described egress and interference from the branch duct closed at the time is prevented, whenever either source is exhausted by its respective device. 15 It is understood that as each double-acting valve C, C', E, E' or F, F' is freely suspended, it is very sensitive and hence opens and closes on the slightest pressure. Thus when the several parts are in the position shown in Fig. 1, the ports B' and B² 20 are open while the ports B and B³ are closed, that is, the pneumatic or other device connected with the duct A is exhausted by the action of the device connected with the 25 branch duct D². In a like manner, the pneumatic or other device connected with the duct A can be exhausted from the device connected with the duct D⁶, if the valve F' shall have been opened and the valve F closed, so that the duct D⁵ is connected by 30 way of the port B⁵ with the ducts A², D³, whereby the valve E' is opened and the valve E closed, so that the duct D³ is connected by the port B³ with the ducts A', D' and 35 by way of the open valve C' and port B' with the duct A and the pneumatic connected therewith.

It is understood that by the use of the device an organ pipe V (Fig. 4), can be made 40 to speak from a selected source D, D², D⁴ or D⁵, put "on" through the respective device J, J', J², through the actuation of the device Y' and its stop pallet R². It is to be further understood that the devices Y and Y' (Figs. 45 3 and 6) and the devices shown in Fig. 4, represent old structures which are in general use, being merely shown for the purpose of illustrating the parts with which the present invention is connected in order to 50 properly operate. In the construction of the first-mentioned devices, the device Y' includes a stop pallet R² controlling the valve R³ through a connecting rod P², and in turn controlled by the stop, its chamber S being 55 as usual, supplied with constant wind pressure. In the device Y the construction is closely similar except that the control is through a connecting rod P, by a key from the manual instead of by means of a stop. 60 In Fig. 4 the valve U which controls the part of the organ pipe V, is actuated by a pneumatic T and the chamber W is, as usual supplied with a constant wind pressure. Thus the organ pipe may be made to speak 65 in various ways, and the different connec-

tions D, D², D⁴, D⁵ for instance, from a key on the great or lower key board, the upper key board, the pedal key board etc., are enabled to be independently actuated without danger of the wind getting from one connection into any other connection, on account of the double valves supplied by the present invention. This is highly important, inasmuch as when one connection is actuated, the other connections, whose respective keys are not pressed down, are all subjected to wind pressure which would escape were it not prevented from doing so. 70 75

Having thus described my invention, I claim as new and desire to secure by Letters Patent:

1. A selecting device of the character described provided with opposite ports, a duct leading to said opposite ports, branch ducts connected with the said ports, a suspended valve for closing one port while opening the other and vice versa, a diaphragm chamber, a diaphragm therein, and a connection between the said diaphragm and the said valve, the said diaphragm having a cushion for engagement with a wall of the diaphragm chamber. 90

2. An organ provided with a primary, manuals and a selecting device intermediate the said primary and the said manuals, the selecting device having an operating duct connected with the said primary, the duct terminating in opposite ports, branch ducts into which open the said ports and connected with the manuals, suspended gravity valves 100 for the said ports, a connection between the said valves, and means for vertically adjusting the said valves.

3. An organ provided with a primary, manuals and a selecting device comprising 105 an operating duct connected with the said primary and terminating in a pair of opposite ports, a pair of branch ducts into which open the said ports, one of the branch ducts leading to a manual, a pair of connected valve members controlling the said ports, a second pair of opposite ports into which terminates the other branch duct, and a second pair of connected valve members for the said second pair of ports, and a 110 second pair of branch ducts connected with the second pair of ports, one of the ducts of the second pair of ducts connecting with a manual and the other duct of the second pair terminating in a third pair of opposite 115 ports, a third pair of connected valve members for the said third pair of ports, a fourth pair of branch pipes leading from the said duct to manuals, the said selecting device having a diaphragm chamber opposite each pair of valve members, a diaphragm in each chamber, and a connection between each diaphragm and its respective pair of valves. 120 125

4. An organ having a primary, a manual, 130

- and a selecting device having opposite ports and an operating duct connected at one end to the primary and opening at its opposite end into the said ports, branch ducts connected to the manual and into which the said ports open, a suspended valve for closing one port while opening the other and vice versa, a diaphragm chamber, a diaphragm therein, and a connection between the said diaphragm and the valve, the said diaphragm having a cushion for engagement with a wall of the diaphragm chamber.
- 5 to the primary and opening at its opposite end into the ports, branch ducts connected to the manual and into which the said ports open, a suspended valve for closing one port while opening the other and vice versa, a diaphragm chamber, a diaphragm therein, and a connection between the said diaphragm and the valve, the said diaphragm having a cushion for engagement with a wall of the diaphragm chamber.
- 10 whereby one port will be open when the other port is closed, the upper portions of said flexible members having vertical slots, and fastening members extending through the slots whereby to secure the valve in adjusted position.
- 15 5. An organ having a primary, a manual, and a selecting device having opposite ports and an operating duct connected at one end

In testimony whereof I have signed my name to this specification in the presence of two subscribing witnesses.
